UNITED STATES PATENT OFFICE

119,823

DESIGN FOR AN OPERATING HANDLE FOR ELECTRIC CONTROLLING DEVICES

Clifford Brooks Stevens, Shorewood, Wis., assign-
or to Cutler-Hammer, Inc., Milwaukee, Wis., a
corporation of Delaware

Application January 18, 1940, Serial No. 89,560

Term of patent 14 years

To all whom it may concern:

Be it known that I, Clifford Brooks Stevens, a citizen of the United States and a resident of Shorewood, in the County of Milwaukee and State of Wisconsin, have invented a new, original, and ornamental Design for an Operating Handle for Electric Controlling Devices, of which the following is a specification, reference being had to the accompanying drawing, forming part thereof.

Figure 1 is a top plan view of an operating

handle for electric controlling devices incor-
porating my new design.

Fig. 2 is a side elevational view thereof, and
Figs. 3 and 4 are rear and front elevational
views, respectively, of said operating handle.

I claim:

The ornamental design for an operating han-
dle for electric controlling devices, substantially
as shown.

CLIFFORD BROOKS STEVENS.
